UNITED STATES PATENT OFFICE.

OSCAR BURNS, OF MOORCROFT, WYOMING, AND CARRIE M. WOOD, OF SANTA ANA,
CALIFORNIA.

OIL BURNER.

Application filed December 22, 1923. Serial No. 682,177.

To all whom it may concern:

Be it known that we, OSCAR BURNS and CARRIE M. Wood, citizens of the United States, residing at Moorcroft, in the county 5 of Crook and State of Wyoming, and Santa Ana, in the county of Orange and State of California, respectively, have invented certain new and useful Improvements in Oil Burners, of which the following is a specification.

Our invention relates to oil burners and provides a simple and efficient burner of such construction that the oil will be thoroughly vaporized in its flow to the discharge point and will issue at such point in a quickly combustible condition. The invention also provides novel means whereby the flow of vapor at the burning point will be automatically controlled and will be completely cut off in the case of a sudden increase of pressure. The invention also provides novel means whereby, in the event of some accident or other cause producing an overflow of oil, the flow to the burner will be automatically cut off. Other incidental objects of the invention will appear in the course of the following description, and the invention resides in certain novel features which are illustrated in the accompanying drawings and will be particularly pointed out in the appended claims.

In the drawings:

Figure 1 is a side elevation of a burner constructed in accordance with our invention;

Fig. 2 is an elevation viewing the burner at a right angle to the view point in Fig. 1, and

Fig. 3 is an enlarged sectional elevation, the section being taken on the line 3—3 of Fig. 1.

In the drawings, the reference numeral 1 indicates the main supply pipe which is equipped with a rotary cut-off valve 2 of any suitable form having a stem 3 which is extended laterally to one side, as clearly shown in Figs. 2 and 3. In installing our improved burners, it is the intention to supply fuel and compressed air from a central station and equip the plant employing the burner with suitable storage tanks in which a supply of fuel and compressed air may be maintained. These tanks will be

connected with the supply pipe 1 through any convenient fittings, but it will be understood, of course, that the burners may be employed in connection with local storage tanks not connected with a central supply station.

The main supply pipe 1 is connected 60 through an elbow 4 with a lateral branch pipe 5, which branch is connected by a T-coupling 6 with other branch pipes 7 communicating directly with the lower ends of conveying and vaporizing pipes 8 which rise vertically from the ends of the branches 7 and communicate directly with horizontal pipes 9 arranged in parallelism and communicating with downwardly extending pipes 10, the said pipes 10 together with the 70 pipes 8 forming a substantially rectangular system of conduits or conveyers whereby the fuel is carried around the burner so as to be exposed to the heat given out therefrom. The lower ends of the pipes 10 are connected by branches 11 similar to the branches 7 and connected by a T-coupling 12 with a lateral feed pipe 13 extending inwardly toward the pipes 7, as clearly shown in Figs. 2 and 3. Elbow couplings, as 14, are provided to connect the pipes 8 and 9, the pipes 9 and 10 and the pipes 10 and 11, as will, of course, be understood, and at the lower ends of the pipes 10 screw plugs 15 may be provided so as to facilitate cleaning of the 85 apparatus in the event that sediment should collect in the couplings. The inner end of the pipe 13 is connected by an elbow 16 with a nipple 17 upon which is fitted an ignition pan 18. A coupling sleeve 19 is connected 90 to the upper end of the nipple 17 and provided with a flange 20 at its upper end. From the upper end of the sleeve 19, a pipe 21 rises and a valve stem 22 extends entirely through the said pipe, as shown clearly in Fig. 3, the lower end of the said stem being equipped with a cut-off valve 23 within the coupling sleeve 19 and adapted to abut the lower end of the pipe 21 in the event of some sudden excessive flow of oil through 95 the several pipes. The upper end of the stem 22 is secured in a plug 24 which closes the upper end of an outer pipe 25 which extends down around the pipe 21 in spaced relation thereto and is equipped at its lower 100 end with a flange 30 adapted to rest on the

105

flange 20, a hollow governor weight 31 encircling the pipe 25 and resting on the flange 30.

The valve stem 3 is prolonged so that it 5 will extend to a point below the pipe 13 and is supported from said pipe by a hanger 26 which may be of any convenient or approved construction, the end of the stem being rotatable in the lower end of the hanger, as 10 will be readily understood. A drip pan 27 is secured upon the stem 3 immediately below the ignition pan 18 and a ball or rolling weight 28 is loose within the said pan. The pan, as shown clearly in Fig. 1, is secured 15 upon the valve stem 3 near one end so that the greater portion of the pan projects to one side of the stem and consequently an accumulation of oil in said pan will cause it to overbalance and turn to the position 20 shown in dotted lines in Fig. 1, thereby rocking the valve stem 3 and turning the valve 2 to cut off position so that the flow of oil will be arrested and the danger of conflagration or other serious damage will 25 be averted. The turning of the pan and the stem 3 will be accelerated by the provision of the ball or rolling weight 28 which is normally placed at that end of the pan nearer the valve stem, as shown in Fig. 1. When 30 an accumulation of oil, however, tends to tilt the pan, the ball will at once roll to the lower end of the tilted pan and will hold it in that position so that the cut-off valve 2 cannot be prematurely opened.

35 A controlling valve 29 is fitted in the elbow 4 so that the flow of oil to the burner may be cut off or regulated as desired. By opening the valve to a greater or less degree, a more or less intense flame may be 40 produced at the ignition point and, consequently, the intensity of the fire may be easily controlled.

It is thought the operation of the burner will be readily understood. When it is desired to obtain heat at the burner, the pipe 25 is raised thereby lifting the flange 30 from the flange 20 and, if the valve 29 be then opened, oil will flow through the several pipes and be discharged through the 50 lower end of the pipe 25 over the flange 20 into the ignition pan 18. When this pan is filled, the governor weight 31 and pipe 25 are permitted to drop and the flow will then be cut off. The oil in the pan 18 is ignited 55 and the flame therefrom will play upon the nipple 17, the coupling sleeve 19 and the parts above the same so that the oil trapped therein will be thoroughly vaporized and if it be permitted to escape will at once ignite 60 at the lower end of the pipe 25 between the flanges 20 and 30 and will burn in a hot blue flame. When the oil thus supplied to the ignition pan has been consumed, the pipe 25 is again lifted and the vapor then issuing 65 from the lower end of the same is ignited,

combustion then taking place between the flanges 20 and 30 as long as fuel is permitted to flow through the pipe 5 and the several pipes leading therefrom. As the pressure of the oil in the pipes rises and falls, the weight 31 will be lifted and permitted to drop and, consequently, the escape of the oil will be automatically regulated so that, if from any reason the temperature of the burner should fall below the point necessary to properly vaporize the fuel, the pipe 25 will seat upon the flange 20 and will cut off the flow so that no unvaporized oil will be permitted to escape. Should there be an excessive increase in the pressure of the fuel, the weight will be lifted to such an extent that the valve 23 will be seated against the lower end of the pipe 21 and the flow entirely cut off. It will be readily noted that the fuel is forced to rise through the pipe 21 and overflow at the upper end thereof where it is received within the pipe 25 and then flows downwardly to and between the flanges 20 and 30. The lower side of the flange 30 is preferably slightly flared so that it will seat firmly upon the upper side of the flange 20 and thereby positively cut off the flow when the burner is not to operate. It will also be readily noted that we provide a conveying or feeding pipe at each side of the burner so that the flame and heat generated at the ignition point of the burner will play upon a very appreciable length of pipe and, therefore, when the oil reaches the discharge point, it will be thoroughly vaporized and will quickly ignite so that the combustion will be perfect and a flame of any desired intensity may be obtained by manipulating the controlling valve 29. The burner is simple in construction, its parts are compactly arranged, and it is not apt to get out of order.

Having thus described the invention, we claim:

1. In an oil burner, the combination of a 110 nipple, means for supplying fuel to the nipple, a pipe rising from said nipple, the lower end of the pipe being secured in the nipple and constituting a valve seat, a governor device housing said pipe and responsive to the pressure of the fuel in the nipple and the pipe, an outlet device carried by said governor member and encircling the pipe and adapted to seat upon said nipple, a valve stem carried by the governor member and extending axially through the pipe into the nipple, and a valve secured on the lower end of the stem and adapted to seat against the lower end of the pipe.

2. In an oil burner, the combination of a 125 nipple having an exterior flange at its upper end, means for supplying fuel to said nipple, a governor member mounted above the nipple and responsive to pressure of the fuel, an external annular flange at the lower end 130

of said governor member adapted to seat upon the flange on the nipple whereby to cut off the flow of fuel or be spaced therefrom to provide a discharge space at which fuel may be ignited, a valve stem secured in said governor member and extending axially therefrom into the nipple, and a valve carried by said stem and adapted to seat internally at the upper end of the nipple whereby to cut off the flow under excessive pressure.

In testimony whereof we affix our signatures.

OSCAR BURNS. [L.S.]
